UNITED STATES PATENT OFFICE.

JOSEPH ALBERT RONCHETTI, OF WOONSOCKET, RHODE ISLAND, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,082,556.

Specification of Letters Patent. Patented Dec. 30, 1913.

Application filed April 19, 1909. Serial No. 490,918.

To all whom it may concern:

Be it known that I, JOSEPH A. RONCHETTI, a subject of the King of Italy, residing at Woonsocket, in the county of Providence and State of Rhode Island, have invented certain new and useful Improvements in Type-Writing Machines, of which the following is a full, clear, and exact description, such as will enable others skilled in the art 10 to which it appertains to make and use the same.

This invention relates broadly to type-writing machines and more particularly to the escapement mechanism of a machine of 15 a type designed to effect printing without producing noise.

In typewriting machines as hitherto constructed, a large part of the noise incident to the operation thereof has been produced 20 by the clicking of the parts of the escapement mechanism, and one of the objects of my invention is to overcome this objection and render the operation of the escapement mechanism substantially noiseless.

25 Other objects will be in part obvious and in part pointed out hereinafter.

The invention accordingly consists in the features of construction, combinations of elements and arrangement of parts which 30 will be exemplified in the construction hereinafter set forth, and the scope of the application of which will be indicated in the following claims.

In the accompanying drawings, wherein 35 are illustrated several of various possible embodiments of the invention, Figure 1 represents a plan view thereof, showing the escapement wheel resting upon the fixed dog; Fig. 2 is a side view of the escapement mechanism with the parts similarly positioned; Fig. 3 is a section on line 3—3 of Fig. 1, looking in the direction of the arrow; Fig. 4 is an end view of Fig. 2 of the rocker member, and the parts carried thereon, the 45 escapement wheel being omitted; Figs. 5 and 6 are views similar to Figs. 1 and 2 respectively, showing the position of the parts when the rocker member has been swung to carry the movable feed dog into engagement 50 with the escapement wheel; Fig. 7 is a sectional view on lines 7—7 of Fig. 5, looking in the direction of the arrow; Figs. 8 and 9 are plan and side views respectively of the parts shown in Fig. 1, the movable dog be-

ing shown in the back-spacing position; Fig. 55 10 is a sectional view on line 10—10 of Fig. 8, looking in the direction of the arrow; Fig. 11 shows, in plan, a different embodiment of the escapement, the tooth of the escapement wheel resting against the fixed 60 dog; Fig. 12 is a side view of the mechanism shown in Fig. 11; Fig. 13 is a plan view of this modification of the escapement, wherein the escapement wheel rests upon the movable dog; Fig. 14 shows another embodiment of my invention, with the escapement wheel resting against the movable 65 dog; Fig. 15 is a view in side elevation of the mechanism shown in Fig. 14; and Fig. 16 is a plan view of the escapement shown 70 in Fig. 14 with the rocker depressed, whereby a tooth of the escapement wheel rests against the fixed dog.

Referring now to the drawings, and particularly to the embodiment of my invention illustrated in Figs. 1 to 10 inclusive, 1 represents a portion of the framing of the machine, which supports, as by means of lugs 2, pivot screws 3, and upon the latter oscillates the vibratory rocker member 4. 80 This rocker member carries the fixed or detaining dog 5, which, as shown, is placed upon the upper side of the rocker and is fixed in position thereon, as by means of clamp screws 6. On the same side of rocker 75 member 4, there is pivoted at 7 a lever 8 provided with an inside wiper cam 10. Lever 8 adjacent the cam portion 10, projects downwardly as at 11, in order to secure greater area, Fig. 4. The cam 10 may be 90 closed, as at 11', or it may be open at that point if desired. The opposite end of cam lever 8 is connected with a coil spring 12 attached to the post 13. A leaf spring 14 is fixed to lever 8 at 15 and the end of this 95 spring rests against a cam roller 16, which is rotatably mounted on a pivot screw 17 in the ear 18 of the movable dog 20, which, as shown, is mounted upon a bushing 21 clamped to the rocker member by the screw 100 22. A guard or cap 23 is clamped against the other end of bushing 21 by the clamp screw 22, the swinging dog vibrating between this cap and the rocker member 4. The escapement shaft is shown at 24, and 105 25 represents an escapement wheel provided with teeth as 26 and 27. The rocker member 4 may be oscillated, as by means of an

2

arm 28, which may be connected to the universal bar of the typewriting machine or other movable part thereof which is actuated through a connection with the key levers or space bar. Having thus described this embodiment of my invention, the operation thereof may now be understood: With the parts in normal position, a tooth of the escapement wheel is resting against the movable dog 20, holding it in the position shown in Figs. 5 and 7, and at this point it may be noted that the face of the movable dog 20 is placed slightly in advance of the face of the fixed dog 5, as shown in these figures. When the rocker member is depressed to the position shown in Figs. 1 to 3, the tooth of the escapement wheel will pass from the movable dog to the fixed dog and the tooth 30 of the movable dog will swing rearwardly, as shown in Fig. 1, being forced to that position by means of spring 12 acting upon lever 8, thus bringing cam 10 to the position shown in that figure. Then, when the rocker member 4 is swung upwardly, the tooth 26 is released from the fixed dog, and the tooth 27 of the escapement wheel engages the tooth 30 of the movable dog, forcing that dog to the position shown in Figs. 5, 6 and 7, where the tooth 27 rests upon the movable dog whose motion is arrested by means of the cam roller 16 engaging the cam surface 10 of the lever 8 and moving that cam to the position shown in Fig. 5 against the resistance of spring 12. In that position, roller 16 rolls against the surface of cam 10 as far as it can until the cam surface stops it from going any farther, thus effecting the arresting of the movable dog and the associated parts in a silent manner. Upon swinging the rocker member downwardly again, as shown in Figs. 2 and 3, the movable dog is again released and flies outwardly as before, being impelled by cam 10 and spring 12; and it will be noted that the cam, in conjunction with spring 12, arrests the movable dog in an intermediate position, spring 14 at all times holding the roller 16 against the surface of the cam. When it is desired to effect back spacing, the escapement wheel 25 may be pushed rearwardly, thus forcing it from the position shown in Fig. 5 to the position shown in Fig. 8. This permits the tooth 30 to pass over the tooth 26, after which, upon the release of the back-spacing key (not shown), the tooth 26 will rest against the tooth 30 of the dog 20 and the parts will assume the positions shown in Fig. 5. During the back-spacing operation, the roller 16 will leave the cam surface 10 and bend spring 14 temporarily, as shown in Fig. 8, and at the same time lever 8 will be swung in the opposite direction, slightly expanding the spring 12; that is, the pressure of spring 14 will counterbalance the tension of spring 12 when

the parts are in the position shown in Fig. 8. In the embodiment of my invention shown in Figs. 11 to 13 inclusive, the positions of the parts are reversed. In this construction, the movable dog is pivoted at 32 and is provided with cam surfaces 33 and 34, the curves of which have a larger radius than that of the cam roller 35 which engages said cam surfaces. The cam roller 35 is journaled upon a stud 36 secured to a bifurcated arm 37 pivoted, as at 38, to the rocker member, said arm having a retractile spring 40 connected therewith, which tends to draw the same to the right. In the operation of this device, the rocker has been depressed as shown in Figs. 11 and 12, and the tooth 26 of the escapement wheel is supported by the fixed dog 5. Upon swinging the rocker upwardly, the tooth 26 will be disengaged from the fixed dog, and the tooth 27 will be engaged with the tooth 30 of the movable dog, and that dog moved from the position shown in Fig. 11 to that shown in Fig. 13. During that movement, the cam surface of the movable dog engages the roller 35, forcing it from the position shown in Fig. 11 to that shown in Fig. 13, where the motion of the dog will be arrested by the cam surface 34 against the tension of the spring 40. Inasmuch as the cam surface 34 is of larger radius than that of the roller 35, the arresting of the movement of the dog will be substantially noiseless.

Referring now to the embodiment of the invention illustrated in Figs. 14 to 16 inclusive, the movable dog 20 is provided with a cam slot 41, which engages the roller 42 on the swinging arm 43, the movement of the swinging arm being resisted by means of the tension spring 44, which tends to pull that arm to the position shown in Fig. 16. In Figs. 14 and 15, the parts are shown in their normal positions of rest, in which the escapement tooth 26 rests against the movable dog 30, such dog having been brought to such position of rest by the swinging movement of the roller in the cam groove 41 against the tension of spring 44, thus noiselessly arresting the motion of the dog. Upon moving the rocker member 4 downwardly, the fixed dog 5 engages with tooth 26 of the escapement wheel, and the movable dog 30 will jump forward as shown in Fig. 16, being impelled to that position by means of the coiled spring 44, pulling the arm 43 in a straight line with the spring 44, roller 42 engaging with the cam slot 41 during that operation.

It will, accordingly, be seen that I have provided mechanism well adapted to attain, among others, all the ends and objects above pointed out in an exceedingly simple yet efficient manner.

The embodiments of the invention herein described for carrying out the invention each

comprise comparatively few parts, and there is, therefore, little likelihood of any part thereof becoming deranged. It will be observed that, inasmuch as no compact or ⁵ cushion of movable parts takes place in the escapement, no noise can be produced, and yet the parts can be accurately and positively arrested in position to which they are adapted to be moved.

10 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by United States Letters Patent is:

1. In an escapement mechanism, the combination with a rack member to be spaced, of a movable feed dog pivotally supported ²⁵ at one end coöperating therewith, a cam member pivotally supported intermediate its ends adapted to coact with said dog at one end, and spring means coacting with the other end of said cam member adapted to be tensioned to silently arrest the movement of the dog when engaged by the rack member.

2. In an escapement mechanism, in combination with a rack member adapted to be spaced, of a movable feed dog coöperating ³⁵ therewith, and a concave cam member having one end yieldingly connected with a relatively fixed part and its other end adapted to coact with said movable dog to silently arrest its movement.

3. In an escapement mechanism, the combination with a rack member to be spaced, of a movably mounted feed dog adapted to coact therewith, a stud carried by said dog, and a concave cam member coacting with ⁴⁵ said stud and yieldingly held in operative relation thereto.

4. In an escapement mechanism, in combination with a rack member to be spaced, of a movable feed dog coacting therewith, and ⁵⁰ a pivotally mounted member connected with said dog having an oscillating movement upon its support adapted to be held in an intermediate position when said dog is out of engagement with the rack member.

5. In an escapement mechanism, the combination with a member to be spaced, of a ⁸⁰ rocker member, fixed and movable dogs carried on opposite sides of said rocker member, and a movable member connected with the movable dog and on the same side of the rocker member as said fixed dog adapted to arrest the movements of said movable dog.

6. In an escapement mechanism, the combination with a member to be spaced, of a ⁸⁵ rocker member, fixed and movable dogs car-

ried on opposite sides thereof, and a movable member mounted upon said rocker member on the same side thereof as said fixed dog and connected with said movable dog, adapted to arrest the movements of said movable ⁷⁰ dog when the same is engaged with the member to be spaced, and to return the same to normal position after movement.

7. In an escapement mechanism, the combination with a part to be spaced, and a ⁷⁵ rocker member carrying a fixed and a movable dog, of means for arresting the movements of the movable dog, comprising an arm connected therewith pivoted intermediate its ends and adapted to interpose a ⁸⁰ yielding resistance to the movements of said movable dog and ultimately to arrest such movements.

8. In an escapement mechanism, the combination with the part to be spaced, and a ⁸⁵ rocker member carrying a fixed and a pivotally mounted dog, of a pivotally mounted spring-actuated member carried by the rocker member, which is connected with the movable dog and normally holds the same in ⁹⁰ an intermediate position, but which permits the same to be swung to either side of such position.

9. In a typewriting machine, in combination, a member adapted to be spaced, means ⁹⁵ for effecting spacing thereof, comprising a rocker member provided with a fixed dog and a movable dog adapted to be engaged with the spaced member when said rocker member is actuated, and a pivotally-mounted ¹⁰⁰ spring-actuated member carried by the rocker member which is connected with the movable dog and normally holds the same in an intermediate position, but permits the same to be swung to either side of such position and arrests the same when swung without impact or concussion.

10. In an escapement mechanism for typewriting machines, in combination, a spaced member, a member carrying a fixed and ¹¹⁰ swinging feed dog, means for effecting a relative movement between said elements whereby said dogs are engaged alternately with said spaced member, means connected with said swinging dog for holding the same normally in an intermediate position and for arresting the movement thereof when the same is engaged with said spaced member and moved thereby and a spring for controlling said means.

11. In an escapement mechanism for typewriting machines, in combination, a member to be spaced, a vibratory dog carrier provided with a fixed detaining dog, a swinging feed dog and a swinging member mounted ¹²⁵ upon opposite sides of the dog carrier, which latter coöperates with said movable feed dog to arrest the same when it has been engaged with the spaced member and moved thereby into substantial alinement with the detaining ¹³⁰ 180

dog, said swinging member being adapted to reposition said swinging dog when the same has been disengaged from the member to be spaced.

5 12. In escapement mechanism for typewriting machines, the combination of a member to be spaced, a rocker member, a feed dog pivotally-mounted thereon and capable of occupying different positions, a 10 swinging member carried by the rocker member having a cam portion engaged with said feed dog adapted to limit the movement thereof when engaged with the member to be spaced and moved thereby, a spring 15 adapted to hold said movable part in engagement, and means which coöperates with said swinging member for returning said feed dog to a normal position.

13. In escapement mechanism for typewriting machines, the combination of a member to be spaced, a rocker member, a feed dog pivotally-mounted thereon, adapted normally to rest in an intermediate position, but capable of being swung to either 25 side of such position, a swinging member co-operating with said feed dog, one of said last named parts being provided with a concave cam portion and the other thereof with a projecting portion engaging said cam, said 30 swinging member being adapted to arrest the movements of said feed dog when the same is moved to either side of its normal position, and spring means coöperating with said swinging member for arresting the feed dog 35 in its intermediate position.

14. In an escapement for typewriting machines, the combination with the member to be spaced, of spacing means therefor, comprising a vibratory dog-holder, a swinging 40 feed dog, a swinging stop member pivoted intermediate its ends connected with said feed dog and adapted to arrest the movement thereof when the same has been engaged with the member to be spaced and 45 moved thereby, and independent pivots upon said rocker member for each of said swinging elements.

15. In escapement mechanism, the combination with a part to be spaced, of spacing means therefor, comprising a vibratory dog-holder, a swinging feed dog carried thereby, a swinging stop member carried thereby, one of said last mentioned elements being provided with a cam opening and 55 the other with a projection engaging with said cam, and a spring connected with said swinging stop member.

16. In an escapement mechanism for typewriting machines, the combination with the member to be spaced, of spacing means therefor, comprising a vibratory dog-holder, a swinging feed dog carried thereby, a swinging stop arm carried thereby, one of 60 said last mentioned elements being provided

with a cam opening and the other thereof with a cam projection extending through said opening, a spring upon one of said parts for maintaining said projection in engagement with the walls of the opening in the other part, and a spring connected with said stop arm and adapted to urge the same to such position as will arrest the feed dog in a normal intermediate position.

17. In escapement mechanism for typewriting machines, the combination with the part to be spaced, of spacing means therefor, comprising a vibratory dog-holder, a swinging feed dog mounted thereon, a swinging stop arm carried by the dog-holder, said stop arm being provided with a cam aperture, and a leaf spring mounted upon said stop arm and engaging said projection to hold the same in engagement with the wall of said cam aperture.

18. In an escapement for typewriting machines, the combination with the member to be spaced, of a rocker member, a fixed dog on one side of said member, a pivotally mounted movable dog secured to the opposite side of said member, and means secured to said rocker member on the same side as said fixed dog for silently arresting the movement of said movable dog.

19. In escapement mechanism for typewriting machines, in combination, a member to be spaced, spacing means therefor including a rocker member, a fixed dog on one side and a movable dog on the opposite side of said rocker member, and spring actuated means for controlling the position of said movable dog, said means coacting with said movable dog to positively limit the movement of the movable dog when engaged by the member to be spaced.

20. In escapement mechanism for typewriting machines in combination, a member to be spaced, spacing means therefor including a rocker member, a fixed dog on one side and a movable dog on the opposite side of said rocker member, spring actuated means for controlling the position of said movable dog, said means coacting with said movable dog to positively limit the movement of the movable dog when engaged by the member to be spaced, and a cap for holding said movable dog in position.

21. In escapement mechanism for typewriting machines, in combination, a member to be spaced, spacing means therefor including a rocker member, a fixed dog on one side and a movable dog on the opposite side of said rocker member, and a spring actuated pivotally mounted cam member for silently arresting the movement of the movable dog and for positively controlling the position of the movable dog when engaged by the member to be spaced.

22. In escapement mechanism for type-

writing machines, in combination, a member to be spaced, spacing means therefor including a rocker member, a fixed and movable dog on opposite sides of said rocker member, spring actuated means for controlling the position of said movable dog, said means coacting with said movable dog positively to limit the movement of the movable dog when engaged by the member to be spaced, and spring means for holding the movable dog and means in constant engagement.

23. In escapement mechanism for type-writing machines, in combination, a rocker member, a fixed dog and a movable dog associated therewith, and a cam member for controlling the position of said movable dog, said cam member and said movable dog be-

ing positioned on opposite sides of said rocker member.

20

24. In escapement mechanism for type-writing machines, in combination, a rocker member, a fixed dog and a movable dog associated therewith, and a pivotally mounted spring actuated cam member for controlling the position of said movable dog, said pivotally mounted spring actuated cam member being positioned on the opposite side of said rocker member.

25

In testimony whereof I affix my signature, 30
in the presence of two witnesses.
